UNITED STATES PATENT OFFICE.

FURMAN M. KANDLE, OF ATLANTIC CITY, NEW JERSEY.

FLOOR AND CEILING CONSTRUCTION.

Application filed June 12, 1925. Serial No. 36,695.

This invention relates to building constructions and more particularly to a fire-proof floor and ceiling construction in which concrete or analogous cementitious material is used in connection with suitable I-beams and mesh for forming the ceiling in the floor.

An object of the invention is to provide a structure of this type in which the floor and ceiling are prepared at the same time and in which the floor and ceiling are both tightly stretched and no sagging will be permitted; also, to provide a structure as specified, in which no boarding, lathing, or the like is necessary, and one which is well arched to provide the necessary strength.

Another object of the invention is to provide a structure which may be prepared in a shop and may be installed with relatively cheap, unskilled labor in a quick, accurate manner, and one which provides a rigid building thoroughly braced and also provides space or conduits for electric wires or the like, and further may be utilized for the purpose of ventilation of rooms, closets, or the like.

Other objects of the invention will appear in the following detail description and in the accompanying drawings wherein:

Figure 1—is an elevation of a section of the mesh used in the improved floor and ceiling construction.

Figure 2—is a fragmentary side elevation of a section of the metallic mesh.

Figure 3—is a fragmentary section through the floor and ceiling structure.

Figure 4—is a fragmentary horizontal section through the floor and ceiling structure.

Figure 5—is a fragmentary vertical section taken on the line 5—5 of Figure 4.

Referring more particularly to the drawings, in constructing a building in accordance with this invention, the frame or skeleton of the building is made of iron or steel construction, and the floors and ceilings are braced by suitable I-beams A which form no part of the present invention and which are used extensively in the construction of buildings. The present invention relates entirely to the construction between the various I-beams A and in forming the ceiling and floor of a building a plurality of sections of screen, wire, metal, mesh or the like, as indicated at 1 are used and they have their edges connected by suitable plates 2 to provide cylindrical structures, as shown in Fig-

ure 1 of the drawings. When the various cylinders 1 of mesh are in proximity to the floor and ceiling to be formed, the spreaders 3 are inserted within the cylinders and are spread to provide substantially pyramidal sections—as shown in Fig. 1 of the drawings. The spreaders 3 comprise—a pair of substantially U-shaped members 4 and 5, which are pivotally connected by a suitable bolt 6 and held in spaced relation by a spacing sleeve 7. Rods 8 are suspended from the pivot bolts 6 of the spreader structures 3 by suitable wires 9 and are provided for bracing the horizontal or bottom portion 6' of the substantially pyramidal shaped mesh member, as clearly shown in Figure 3 of the drawings. The mesh members are connected in endwise relation, and the edges are connected by lacing. After the various sections 1 have been braced in position and connected in endwise relation as specified, concrete or other cementitious material is placed on the upper surface of the inclined upper sides 11 and 12 of the member 1 filling in the space between the various I-beams A. If it is so desired, cinders or any light material may be used as indicated at 13, and a concrete cementitious surface 14 applied thereon. The plastering for the ceiling is applied to the under or outer surface of the horizontal side 6, eliminating the use of laths, or the like, and consequently eliminating the work necessary for placing the laths.

In making the cementitious filler 13 it is preferable to use a layer of relatively rich mixture as indicated at 13' directly over and engaging the upper sides 11 and 12 of the screen which increases the strength and also securely binds the various elements together in that the mixture flushes into the space at the ends of the various sections and binds the ends of the sections and the heads 10 of the rods together, and with the I-beams A.

While in the foregoing description and in the accompanying drawings, the improved structure has been described and illustrated, as for floor and ceiling constructions, it is to be understood that it may also be embodied in a roof construction or for analogous use wherever it is adaptable without departing from the spirit of this invention.

It is, of course, to be understood, that the invention may be constructed in various other manners and the parts associated in different relations, and therefore, I do not

desire to be limited in any manner, except as set forth in the claims hereunto appended.

What I claim is:

1. In a floor and ceiling construction, a plurality of metal mesh units, **U** shaped spreading members centrally pivoted within said units to provide pyramidal forms with their inclined lower sides in floor material supporting position, and said units disposed in endwise formation between a pair of **I** beams.

2. In a floor and ceiling construction, a plurality of metal mesh units, a pair of **U** shaped spreading members centrally pivoted within said units to form substantially pyramidal forms with their inclined lower sides in floor material supporting position, and a ceiling bracing rod suspended cen-

trally from said spreading members and disposed transversely through said units on the bottom face of said mesh units.

3. In a floor and ceiling construction, a plurality of metal mesh units, a pair of oppositely disposed **U** shaped spreading members, having their free ends pivoted centrally within said units to provide substantially pyramidal forms with their inclined lower sides in floor material supporting position, said units disposed in endwise relation, and a ceiling bracing rod suspended from the pivoted ends of said spreading members and disposed transversely through said units on the bottom face of said mesh units.

In testimony whereof I affix my signature.

FURMAN M. KANDLE.
